T. S. OWENS

SHEET GLASS DRAWING MECHANISM

Filed March 5, 1920

INVENTOR
Thomas S. Owens,
By *Own Hand*, Crampton,
His Atty.

UNITED STATES PATENT OFFICE.

THOMAS S. OWENS, OF TOLEDO, OHIO.

SHEET-GLASS-DRAWING MECHANISM.

Application filed March 5, 1920. Serial No. 363,508.

To all whom it may concern:

Be it known that I, THOMAS S. OWENS, a citizen of the United States, and a resident of Toledo, in the county of Lucas and 5 State of Ohio, have made an Invention Appertaining to Sheet-Glass-Drawing Mechanism; and I do hereby declare the following to be a full, clear, and exact description of the invention, such as will enable others 10 skilled in the art to which it appertains to make and use the same, reference being had to the accompanying drawings, and to the characters of reference marked thereon, which form a part of this specification.

15 This invention relates to sheet glass drawing mechanism, and particularly to sheet flattening means for use in connection therewith.

20 The object of the invention is the provision in a mechanism of the class described, of a flattening table or means over which the glass sheet being drawn passes and by which it is supported and flattened while in a soft pliant or workable condition, the 25 table or means being movable relative to the sheet and having a sheet coating surface of a suitable material to prevent adherence of the soft coating surface of the glass passing thereover.

30 The invention is fully described in the following specification, and while, in its broader aspect, it is capable of embodiment in numerous forms, a preferred embodiment thereof is illustrated in the accompanying 35 drawings, in which,—

Figure 1 is a fragmentary plan view of a mechanism embodying the invention. Fig. 2 is a side elevation of the sheet flattening means thereof. Fig. 3 is a vertical central 40 longitudinal fragmentary section of an apparatus embodying the invention, and Fig. 4 is an enlarged fragmentary section of one of the sheet supporting slide plates.

45 Referring to the drawings, 1 designates a tank containing molten glass from which the sheet is drawn, the glass being supplied to the table from a communicating furnace 2, or from any other suitable source.

50 The drawing chamber 3 of the illustrated apparatus has opposite side walls 4, 4 and is oblong in a horizontal plane with one end portion disposed over the tank 1 in communication therewith and with its opposite end joining and opening into a leer, as is custom-

ary with apparatus of this character and as 55 is well understood in the art.

The sheet 5, which is drawn from the molten glass in the tank 1, in the present instance, is shown as extending upward a distance into the drawing chamber 5 from the tank 1 and then passes over a bending roll 6, or other suitable guiding means, by which its course is changed to a horizontal or substantially so, the sheet then passing lengthwise through the chamber and into 65 and through the adjoining leer.

While the sheet may be drawn by any suitable means, such means preferably comprises two sets of opposed upper and lower edge gripping belts 7, 7 of the endless type. 70 These belts are disposed within the chamber 3 in spaced relation to the guiding means 6 with a set in gripping relation to each edge of the sheet.

The sheet flattening table or means in 75 which the invention particularly resides, is disposed between the bending means 6 and the drawing means and serves not only to support but to flatten the sheet 5 while in a soft condition and during its passage 80 from the guiding means to the drawing means.

The flattening means employed preferably comprises a plurality of long slide plates 8 of metal arranged in parallel relation 85 transversely of the sheet and mounted in position to pass under and support the sheet between the guiding means and drawing means and to have transverse reciprocatory movements relative thereto. These plates, in 90 the present instance, are mounted for movement on a stationary table or plate 9, which extends under the sheet 5 adjacent to the guiding means 6 and has its ends extended through openings in the side walls 4 of the drawing chamber and a distance beyond the same.

If a plurality of slide plates or panels 8 are provided, as in the present instance, the stationary guide table 9 is preferably provided lengthwise thereof with parallel 100 slideways 10 in which the respective plates reciprocate. The slide plates 8 are of sufficient length and have sufficient movement so that substantially one-half of the length thereof is exposed without one edge of the sheet, while the other half is disposed thereunder in supporting relation thereto. The 105 opposite ends of the slide plates are cooled

by the discharge of water thereon from a superposed discharge pipe 17.

- In order that the plates may be prevented from adhering or sticking to the soft glass sheet drawn thereover, the top surface of each plate is coated with a "paste" composition like or similar to that commonly used to coat the inner surfaces of metal molds used for shaping glass articles. One form 10 of this paste which is used quite extensively in glass shaping molds is composed of one gallon of linseed oil, one pound of white shoemaker wax and five ounces of resin, mixed together and boiled. This mixture 15 forms a gluey substance which is applied to the surface of the plates and finely ground sawdust and cork is then sprinkled thereover. The purpose of the paste is to hold the sawdust and cork. There are, however, 20 many other forms of paste used in the glass working art, and while I have particularly described the ingredients of one form of such paste, it will be understood that I am not limited to the use on the slide plates of any 25 particular paste or coating material. The coating of the metal plates with such paste material not only prevents the glass sheet from adhering thereto, but also imparts a smooth polishing surface to the plates which 30 has a smoothing action on the glass surface with which it coacts, thereby tending to smooth out or eliminate any mars or irregularities on the sheet imparted thereto by the bending roll or in any other manner.
- 35 The plates 8 at one end are tied together by a cross-piece 11, which is screwed or otherwise suitably secured to each, and this cross-piece is connected by a pitman or connecting rod 12 to a horizontally revoluble 40 crank-arm 13. This crank-arm is carried by a vertical shaft 14, which receives its power from a drive shaft 15 in worm and worm-wheel connection 16 therewith. The drive shaft 15 may be connected to any suitable 45 source of power.

The plates 8 may be easily and quickly removed from the supporting table 9 for the purpose of repair or to enable freshly paste coated plates to be substituted therefor. In 50 practice the paste on the plates burns and wears off in time and needs to be replaced. The life of a paste coating on the plates depends largely on the conditions of use, in some cases the coating might need replacing after a days run and in other cases it would last considerably longer. The condition of the coated surfaces of the plates can be easily determined by watching the same while in use and also by the action 55 of the plates on the sheet.

In the operation of my sheet flattening and supporting means the flattening plates are preferably continually moved backward and forward under the sheet at a slow speed.

60 I wish it understood that my invention is

not limited to any specific construction, arrangement or form of the parts, as it is capable of numerous modifications and changes without departing from the spirit of the 70 claims.

Having thus described my invention, what I claim as new and desire to secure by Letters Patent, is,—

1. In a sheet glass drawing mechanism a 75 movable sheet flattening means having a paste surface to prevent adherence of a soft sheet thereto, mechanism for reciprocating said means in contact with the sheet being drawn, and means for applying a cooling fluid to the surfaces of the flattening means. 80

2. In a sheet glass drawing mechanism, a drawing chamber, means for guiding and drawing glass in sheet form vertically a distance from a source of supply and then horizontally in said chamber, guide means 85 below a horizontal soft portion of the sheet, metal plates movable transversely of the sheet in flattening contact therewith and guided for movement by said guide means, said plates having removable paste surfaces 90 in contact with the sheet, and means for moving the plate.

3. In a sheet glass drawing mechanism, the combination with a bending roll over 95 which the glass is drawn in sheet form, of a flattening device disposed to act on a surface of the glass after it passes the bending roll, said flattening device comprising a guide table extending transversely of the sheet in spaced relation thereto and extending 100 at its ends beyond the side edges of the sheet, flattening members mounted on the table for movements lengthwise thereof transversely of the sheet and in contact with the sheet, means for reciprocating the members lengthwise of the guide table, and means for applying a cooling fluid to the sheet coating surface of the flattening members with the opposite edges of the sheet. 105

4. In a sheet glass drawing mechanism, 110 a chamber through which glass is drawn in sheet form, means in supporting contact with a soft portion of the sheet and having a member movable transversely of the sheet and through the side walls of the chamber, and means for imparting reciprocating movements to the movable member of said supporting means.

5. In a sheet glass drawing mechanism, 115 a chamber through which glass is drawn in sheet form, a table disposed at one side of a soft portion of the sheet and extending transversely thereof and through and beyond each side wall of the chamber, a sheet flattening member guided by the table for movements transversely of the sheet in flattening contact with a surface thereof and being of a length for one end portion to extend without a side of the chamber when 120 another end portion thereof is disposed in 130

rubbing contact with the surface of a sheet, means without the chamber for imparting reciprocatory movements to the member, and means for cooling each end portion of the flattening member when disposed without a respective side of the chamber.

6. In a sheet glass drawing mechanism, a chamber through which glass passes in sheet form, means in supporting contact with the 10 soft portion of the sheet and having a member movable transversely of the sheet and

through the side walls of the chamber, means without the chamber for imparting reciprocating movements to the movable member of the supporting means, and means 15 for applying a cooling fluid to the sheet co-acting surface of the member without the side edges of the sheet.

In testimony whereof I have hereunto signed my name to this specification.

THOMAS S. OWENS.
